UNITED STATES PATENT OFFICE

ANTON LEDERER, OF VIENNA, AUSTRIA, ASSIGNOR TO W. T. P. HOLLINGSWORTH, OF NEW YORK, N. Y.

DISCHARGE TUBE

No Drawing. Application filed January 3, 1927, Serial No. 158,833, and in Austria September 27, 1926.

It is well known that in electric discharge vessels or tubes containing rare gases such as neon, helium or the like, the potential drop can be reduced by making the electrodes, or 5 at least the cathode, of an alkali metal or of an alloy thereof, so that the ordinary voltages of 110 or 220 volt will be sufficient for the operation of such discharge tubes.

By Austrian Patents Nos. 69,696, 74,448 10 and 74,449 it has further become known that for the purpose of reducing the cathode drop it is by no means necessary that the electrodes consist of an alkali metal or of an alloy of such metals, but that it is sufficient to make 15 a deposit from vapors of the alkali metals at some place in the interior of the discharge vessel, preferably within the region of the electrodes while the electrodes as such may consist of any desired light or heavy metal, 20 such as aluminium, nickel, tungsten or the like. Such discharge vessels may be operated on the ordinary low voltages. The introduction of vapors of the alkali metals into the discharge vessels causes considerable 25 difficulty, however, and the object of the present invention is a process by which the production of such a deposit is greatly facilitated.

According to the present process a mixture 30 of a compound or compounds of one or several alkali metals with one or several suitable reduction agents is introduced into the interior of the discharge vessel and, prior to, or after closing said vessel, a reaction is 35 caused in this mixture by heating. Thereby vapors of alkali metal are formed which are deposited within the vessel.

The discharge vessel, e. g. an electric rare 40 gas lamp or luminous discharge tube is produced in the usual manner; the electrodes may be made of nickel for example. Prior to the exhaustion of the vessel a small quantity of a mixture, for example, of potassium oxide with metallic magnesium is introduced 45 into the discharge vessel and preferably

placed on one of the electrodes whereupon the vessel is exhausted and filled with a rare gas or a mixture of such gases until the desired pressure is reached. The vessel may next be sealed and the deposit produced afterwards, or, vice versa, the deposit may be produced first, and the vessel then sealed. The deposit is produced in such a manner that the mixture placed in the interior of the vessel is caused to react by heating. In this reaction the magnesium combines with the oxygen of the potassium oxide, freeing vapors of potassium which are deposited within the vessel, leaving magnesium oxide behind. Inasmuch as magnesium oxide has 60 a very high melting point it causes no disturbance during ordinary operation. As a matter of course, it is advisable to make said mixture in molecular proportion of weight.

The heating of the mixture may be effected 65 in different ways, e. g. by placing an induction coil carrying high frequency current, over the discharge vessel in the region where the mixture was placed, that is to say, preferably in the region of the electrode, whereby 70 heating is effected by the inductive action of the high frequency current.

The mixture in which reaction is to be caused, may consist of two or more compounds of the various alkali metals in which 75 case alloys of these metals are formed when the vapors produced by the reaction are deposited. The reduction agents are generally such substances as, after the reaction form compounds that do not disturb the normal 80 operation of the discharge vessel.

What I claim and desire to secure by Letters Patent is:

1. The method of introducing pure alkali 85 metal into an electric illuminating lamp operating by glow discharge in rare gas between cold electrodes, for the purpose of reducing the potential drop, which consists in placing upon the surface of a metal member within the lamp a mixture consisting of an oxide of

at least one alkali metal with at least one reducing metal the oxide of which is stable and substantially non-volatile at the operating temperature of the lamp, and heating said metal member sufficiently to release alkali metal vapor into the tube while the other reduction product remains on said metal member.

2. The method of introducing pure potassium into an electric illuminating lamp operating by glow discharge in rare gas between cold electrodes for the purpose of reducing the potential drop, which consists in placing on an electrode a mixture of potassium oxide and magnesium metal, and heating said electrode sufficiently to release alkali metal vapor.

In testimony whereof, I have hereunto affixed my signature.
